UNITED STATES PATENT OFFICE

2,067,564

AUTOMATIC DAMPER REGULATOR

McClellan Davidson, Hanover, Pa.

Application May 19, 1936, Serial No. 80,625

4 Claims. (Cl. 137—156)

This invention is an improvement in damper regulators and broadly is a pneumatic motor for transmitting power in the form of fluid pressure from its source to any desired instrumentality.

5 One object of the invention is to provide an efficient, cheap and durable damper regulator which is dependable and operates with great smoothness.

Another object of the invention is to prevent 10 access of the actuating fluid to parts of the mechanism that might be injured thereby.

A further object of the invention is to provide 15 a diaphragm actuated damper regulating device in which the damper is actuated by compressed air, said air being compressed in correspondence with the pressure in the boiler governed by the damper, in which device the steam does not contact the diaphragm.

Other objects will appear from the following 20 detailed description taken in connection with the accompanying drawing, Fig. 1 of which represents a vertical cross-section through the device, parts being shown in side elevation, while Fig. 2 shows a perspective view of a cup utilized in the invention.

In the drawing, 1 represents a chamber formed 25 of a bottom 2 and a top 3, the flanges of which are secured together in any suitable way as by bolts and nuts as shown.

30 A flexible diaphragm 4, preferably what is known as a rubber diaphragm, is securely held between the top and bottom and divides the chamber into an upper chamber communicating with the atmosphere and a lower fluid-tight 35 chamber communicating with the source of pressure which is to actuate the diaphragm. For this purpose the under wall of the bottom 2 has an inturned circular flange 5 forming a nozzle which for reasons appearing hereinafter extends 40 nearly to the lowermost position of the flexible diaphragm 4. The lower portion of this circular flange is internally screw-threaded for the attachment of a pipe leading to the source of pressure. In the specific case of a damper regulator 45 as illustrated, the steam chamber of a boiler is the source of pressure.

Seated on the bottom wall of the part 2 is an inverted cup-shaped cap 6 having obtruding portions on the rim to hold the rim a slight distance 50 above said bottom wall. It is important that the height of the sides of the cap 6 is such that the inverted bottom of the cap will always be above the upper edge of the inturned flange or nozzle, and may be in contact with the diaphragm when 55 the latter is in its lowest position.

Water is held in the bottom 2 up to the upper level of the inturned circular flange or nozzle, while the space 7 above this level and below the diaphragm is filled with air.

The relative volumes of the various spaces in 5 the lower chamber is of great importance. The water space between the cap 6 and the inturned flange must be of such volume relative to the air space 7 below the diaphragm that when the steam entering under the cap forces the water 10 under the cap out into such space the water will fill the air space before the level of the water under the cap falls below the rim of the cap.

A weight 8 having a stem 9 passing loosely through an aperture in the top 3, rests on the 15 diaphragm. A support 10 integral with or supported on the top 3 pivotally supports a lever 11 to which the stem 9 is pivotally secured. Suitable weights 12 are slidably secured on the arms of the lever.

The member to be driven, a damper in this 20 instance, not shown, is connected to an arm of the lever 11.

All the above parts except the diaphragm are 25 made of rigid material, preferably cast iron.

The operation of the device is thought to be 30 apparent from the above description.

The device containing water up to the level of 35 the nozzle being mounted on a pipe communicating with a source of pressure, a steam chamber for example, the pressure of the steam is exerted on the upper surface of the water under the cap. The water is forced into the air space 7 compressing the air so that the pressure under the diaphragm equals the pressure of the steam. The 40 diaphragm is raised or lowered accordingly, the air above the diaphragm escaping or entering around the stem 9 or if the stem 9 is made to fit rather closely in the aperture in the top 3, the air enters or escapes through a small aperture provided in the top.

The movement of the diaphragm operates the 45 lever to which the damper or other part to be moved is attached. The weights 12 serve as adjusting means to modify this action as may be desired.

In the operation of this device, the water is 50 automatically kept at the same level. If condensed steam increases the quantity of water it flows over the rim of the nozzle and returns to 55 the boiler. Moreover the pressure fluid, steam, for example, never comes in contact with the flexible diaphragm which is actuated by the compression of the air beneath it.

Having fully described my invention in accord- 55

ance with the United States statutes, what I claim is:—

1. In a damper regulator, a chamber of rigid material, a flexible fluid tight diaphragm dividing said chamber into two parts, the edges of said diaphragm being secured to the side walls of said chamber, a nozzle on the bottom of said chamber extending toward said diaphragm, the chamber being thus adapted to hold water up to the level of said nozzle, an inverted cup-shaped cap resting on said bottom and having outlets at its rim, said cap being of sufficient depth to extend above said nozzle said diaphragm being freely movable relatively to said cap, means resting on said diaphragm for transmitting motion of said diaphragm to a part to be moved, whereby steam entering the nozzle will force water under the cap into the chamber above the cap and compress the air therein to lift the diaphragm.
2. In a fluid motor, a chamber comprising a rigid bottom wall and rigid side walls, and a flexible top wall, a nozzle extending through the bottom wall, an inverted cup-shaped cap resting at separated portions on said bottom wall, the bottom of said inverted cup-shaped cap extending in a plane above the inside rim of the nozzle and said flexible top wall being freely movable relatively to said cap, whereby the chamber is adapted to contain water up to the level of the nozzle and in which the proportions are such that the space adapted to contain water is of greater volume than the space thereabove.
3. Means for transmitting pressure from a fluid

source to a diaphragm in which the fluid does not contact the diaphragm, comprising an open topped vessel, a flexible diaphragm secured thereto and forming the top, a nozzle extending into said vessel, a cap resting at separated portions on the bottom wall of said vessel and extending above the inner end of the nozzle, said vessel being adapted to contain water up to the level of the nozzle tip and to contain air above the water and said flexible diaphragm being freely movable relatively to said cap, that portion of the water containing space under the cap being greater than the air containing space whereby fluid under pressure entering the nozzle forces the water from under the cap and compresses the air to exert the same pressure as the said fluid pressure.

4. In a fluid motor, a chamber comprising a rigid bottom wall and rigid side walls, and a flexible top wall, a nozzle extending through the bottom wall into the chamber, means dividing said chamber into two compartments, said means having an aperture at the bottom affording communication between the two compartments whereby water admitted through the nozzle will fill both compartments to the level of the top of said nozzle, the proportions being such that the space thus adapted to contain water is of greater volume than the volume of the space between the dividing means and the flexible top wall said flexible top being freely movable relatively to said dividing means.

McCLELLAN DAVIDSON.
